UNITED STATES PATENT OFFICE.

CHRISTIAN P. GAA, OF BUCYRUS, OHIO.

POP-VALVE.

1,013,483.

Specification of Letters Patent. Patented Jan. 2, 1912.

Application filed June 21, 1911. Serial No. 634,534.

To all whom it may concern:

Be it known that I, CHRISTIAN P. GAA, a citizen of the United States, residing at Bucyrus, in the county of Crawford and State 5 of Ohio, have invented certain new and useful Improvements in Pop-Valves, of which the following is a specification.

My invention relates to certain new and useful improvements in pop safety valves designed for use in connection with locomotive or other steam boilers, the construction being such as to deaden the noise of exhausting steam or other gases and the efficiency and effective operation of a valve of this type 15 facilitated; and my invention consists of the parts, and the constructions, arrangements and combinations of parts which I will hereinafter describe and claim.

In the accompanying drawings forming 20 part of this specification and in which similar reference characters indicate like parts in the several views; Figure 1 is a side elevation of a pop valve embodying my invention. Fig. 2 is a longitudinal sectional view of the 25 same, with parts in elevation.

In the said drawings I have illustrated an embodiment of my invention as applied to a valve designed for use upon a locomotive or like boiler, and wherein—

30 A represents a safety valve casing of suitable design and dimensions in which the valve, B, is contained, said casing being, preferably, constructed of two parts, one of which, A', is threaded at one end for engagement with the steam pipe of a boiler and is provided with a spider or like guide, C. The part, A', of the casing is also provided with concentric spaced flanges, a, b, one of which, a, is considerably shorter than 35 the other and is provided with a beveled valve seat, c; the other flange, b, extends in line with the upper part, A'', of the casing and is internally threaded and adapted to engage the externally threaded base of a 40 muffler, D, said muffler being double walled or formed with concentric flanges, d, d', which connect at the top. The muffler also has the upper portion of the interior flange, provided with numerous perforations, e, for 45 the escape of steam in a manner well known in this art. The interior flange, d', of the muffler forms a cylinder having parallel inner walls for a portion of its length, said 50 walls thence converging outwardly and merging into a hexagonal or other nut, f,

and being provided with holes, g, connecting with the perforated outer shell, A'', said cylinder forming a shell within which is contained the customary spring, h. The upper part, A'', of the main casing is arranged 55 concentric with the outer wall of the muffler and extends over the muffler, being spaced therefrom, and extending over the nut, f, and having an opening to register with the opening in the nut through which openings 60 pass the regulating screw, i, said screw carrying a nut, j, which is adapted to clamp the section, A'', of the casing in position on the muffler, and said section, A'', of the casing being internally threaded to engage the corresponding threaded base of the muffler. 65

L is a jam-nut engaging the screw and adapted to lock the parts in their adjusted position.

The spring, h, is contained within the internal chamber of the muffler and its upper end is seated against a disk, m, while its lower end is appropriately seated upon a disk, n, which has at its central portion a projection which forms a pivot about which 70 said disk may have a slight rocking motion, said pivot adapted to engage a corresponding depression in the center of the valve.

A leading feature of my present invention is the construction of the valve and the adjusting collar therefor and which parts I will now specifically describe.

The valve is formed with a seating portion, 2, and an overhanging flange, 3, the inner face of which is substantially horizontal 75 or parallel with the upper and lower faces of the valve, and is formed around the underside of its periphery with a beveled seat, 4. This valve is also formed integral with upper and lower guides, the lower guide, O, 80 being mounted within the spider, C, and the upper guide, P, being of piston-like form and of substantial length and having such diameter that it slidably engages the cylindrical portion of the chamber formed within 85 the muffler, said upper guide also receiving and housing the lower portion of the spring and the lower disk upon which said spring is seated.

Within the chamber formed by the concentric flanges of the lower part, A', of the main casing is contained an adjusting collar, Q, adapted to circumferentially embrace and screw into adjustable engagement with the inner flange, a; said collar having a beveled 90

95 inner flange, a; said collar having a beveled 100 inner flange, a; said collar having a beveled 105 inner flange, a; said collar having a beveled 110

portion conforming to the beveled portion, 4, of the valve, and having a straight portion corresponding to the straight portion, 3, between the two beveled faces, 2 and 4, of said 5 valve, the collar being adjustable with relation to these faces of the valve and being held in its adjusted position by a nut, r , threaded in the outer flange, b , of the part, A', of the casing and having a square exterior adapting it for the application of a wrench or like tool.

From the foregoing description it will be seen that the valve is devoid of knife-edges and is accurately guided by its long 15 upper and lower guides; and that there are no knife-edge lips to wear away and change the true working of said valve, as the double guide herein described, insures the perfect seating of the valve under all conditions, 20 and accordingly there is no chance for the valve to "cock", as it is termed, as is more or less common with other types of pop valves. Further, a valve with the construction herein shown and described will stand 25 the greatest amount of service since there is no chance for the valve to bind and no danger of excessive strain being thrown on the valve.

The adjusting collar heretofore mentioned 30 comes in contact with the valve at the outer edge and this is desirable because it is found that the closer the collar is to the edge of the valve, the more steam the valve will pop away. By removing the locking nut, 35 r , the collar can be moved up or down thereby regulating it so as to cause the valve to pop the desired amount of steam, say 1, 2, 3 or 4 pounds of steam, or whatever amount may be desired; when the desired 40 adjustment has been made, the collar may be secured in its adjusted position by means of the locking nut, before mentioned.

In operation, the steam exerts a pressure beneath the valve and overcomes the tension 45 of the spring, compressing said spring and allowing the valve to rise and fully open, and steam to pass up into the double-walled muffler, and the muffler being full of small holes the steam will pass into the 50 outer shell or casing and will thence escape to the atmosphere through the perforations in said casing without excessive noise; in fact without any loud report. The device, therefore, constitutes substantially 55 a noiseless pop valve combined with a muffler having an internal chamber, the area of which is substantially the same as the interior diameter of the opening in the lower part, A', of the casing and through 60 which opening the steam is admitted directly against the valve.

The interior flange of the muffler constitutes a shell in which is contained the spring and the inner wall of this shell 65 forms a cylinder within which operates the

piston like guide, P, of the valve. This arrangement protects the spring from the action of the steam and prevents its rusting.

The high sustained lift of this safety valve allows for the escape of a much greater volume of steam than is possible with the valves of corresponding size as now constructed.

It will be understood that the valve is elevated by the pressure of the steam and the steam passes to the muffler and thence to the atmosphere and when the pressure is reduced the spring operates to seat the valve and shut off the flow of steam.

Having thus described my invention what I claim as new and desire to secure by Letters Patent is:—

1. A pop safety valve having in combination a transversely divided casing provided with a steam inlet at one end and perforations at the outer end for the escape of the exhaust, a muffler within one portion of the casing and separated from the inner wall thereof, said muffler having double perforated walls and having an internal cylindrical portion whose walls are parallel for a portion of their length and thence converge outwardly, a valve within one part of the casing, said casing having a beveled seat for the valve, said valve having a second beveled seating-portion around its circumference, and an adjustable collar surrounding the valve having a seat for the edge seating portion thereof, said valve having a guide projecting from the center of one face and having a tubular portion of substantial length projecting from the opposite face and being of piston-form and slidably engaging the cylindrical chamber of the muffler, a spring within the muffler having one portion entering the space formed by said converging walls and having the other portion seating in the chamber formed by the tubular portion of the valve, said tubular portion serving to prevent the admission of fluid to said spring, an adjusting screw bearing on top of the spring, and a lock nut for holding the screw in its adjustment.

2. A pop safety valve and muffler having in combination; a two-part casing having a steam inlet with a beveled seat surrounding the same, both parts of the casing having adjacent ends internally threaded; a muffler within the casing separated from the wall thereof and provided with double perforated walls, the inner wall of the muffler being formed as a cylinder; and the outer wall having a threaded portion of sufficient length to engage the threaded end of both parts of the casing and to bridge the joint therebetween; a disk valve having a beveled seating portion on the inner face around the edge thereof, and having a second seating portion conforming to the seat

around the steam inlet, the portion of the valve between said seating portions being straight, said valve having a guided stem projecting from one side and having a tubular guide of piston-form and substantial length projecting from the other side and operating in said cylinder; a spring within the cylinder and tubular guide, and supported at one end by the valve; an adjusting screw engaging the other end of the spring; said casing inclosing the muffler and receiving said screw, and having perforations for the escape of steam to the atmos-

phere; and an adjustable collar surrounding the valve having a seat for the edge 15 seating portion of the valve, and having a straight portion within said seating portion conforming to the corresponding portion of the valve.

In testimony whereof I affix my signature 20 in presence of two witnesses.
